UNITED STATES PATENT OFFICE.

JAMES O'LOUGHLIN, OF NEW BRITAIN, CONNECTICUT.

FIRE-EXTINGUISHING APPARATUS.

1,244,637.

Specification of Letters Patent. Patented Oct. 30, 1917.

Application filed April 25, 1917. Serial No. 164,381.

To all whom it may concern:

Be it known that I, JAMES O'LOUGHLIN, a citizen of the United States, residing at New Britain, in the county of Hartford and State of Connecticut, have invented certain new and useful Improvements in Fire-Extinguishing Apparatus, of which the following is a specification.

This invention relates to fire-extinguishing apparatus. Apparatus involving the invention can be used with advantage in widely different connections. The same, however, is of particular utility in extinguishing incipient fires such as occur in households for instance by the clothing of a wearer catching fire. I provide means of a highly effective nature by which a blaze can be quickly put out. While as will be inferred the apparatus can be variously installed, it is of particular importance when stabled, it is of particular importance when her clothing will be ignited either in starting a fire or from some other causes. By the apparatus such a fire can be extinguished.

In the drawings accompanying and forming part of the present specification I have shown in detail one of the several convenient forms of embodiment of the invention which, to enable those skilled in the art to practise the same, will be set forth fully in the following description. I am in no sense, however, restricted to this particular showing; I may depart therefrom in many respects within the scope of the invention defined by the claims following said description.

Referring to said drawings:

Figure 1 is an elevation of the appliance including the incasing cabinet therefor.

Fig. 2 is a front elevation of the apparatus with the doors open.

Fig. 3 is a vertical sectional view of the same.

Fig. 4 is a sectional elevation showing the apparatus in use.

Fig. 5 is a transverse sectional view of the garment and certain coöperating elements.

Fig. 6 is a detail of the upper portion of the garment showing a head-piece.

Fig. 7 is a top plan view of the upper extinguisher member, the garment in folded condition, and means for maintaining such condition.

Fig. 8 is a cross section on the line 8—8 of Fig. 7, looking in the direction of the arrow.

Fig. 9 is a top plan view of the base ring.

Fig. 10 is a cross section on the line 10—10 of Fig. 9, looking in the direction of the arrow.

Fig. 11 is a detail hereinafter described.

Like characters refer to like parts throughout the several views.

When the apparatus is not in use for the purpose intended, it as a matter of saving space is housed in a suitable casing, and

ferred the apparatus can be variously installed in a cabinet as 2 answers satisfactorily in this connection. This cabinet will generally be

mounted in a kitchen. This apartment as is clear, is generally occupied by a housewife or a maid. In her duties about a gas, oil, coal or other stove, it is not infrequent that

her clothing will be ignited either in starting a fire or from some other causes. By the apparatus such a fire can be extinguished.

In the drawings accompanying and forming part of the present specification I have shown in detail one of the several convenient forms of embodiment of the invention which, to enable those skilled in the art to practise the same, will be set forth fully in the following description. I am in no sense, however, restricted to this particular showing; I may depart therefrom in many respects within the scope of the invention defined by the claims following said description.

Referring to said drawings:

Figure 1 is an elevation of the appliance including the incasing cabinet therefor.

Fig. 2 is a front elevation of the apparatus with the doors open.

Fig. 3 is a vertical sectional view of the same.

Fig. 4 is a sectional elevation showing the apparatus in use.

Fig. 5 is a transverse sectional view of the garment and certain coöperating elements.

Fig. 6 is a detail of the upper portion of the garment showing a head-piece.

Fig. 7 is a top plan view of the upper extinguisher member, the garment in folded condition, and means for maintaining such condition.

Fig. 8 is a cross section on the line 8—8 of Fig. 7, looking in the direction of the arrow.

Fig. 9 is a top plan view of the base ring.

Fig. 10 is a cross section on the line 10—10 of Fig. 9, looking in the direction of the arrow.

Fig. 11 is a detail hereinafter described.

Like characters refer to like parts throughout the several views.

shown by dotted lines in this view are at opposite sides of the auxiliary or supplemental band 9, and this supplemental band when the water or other supply is on, is 5 adapted to direct streams between the limbs of the user. It will be understood that the base or floor annulus 7 has jet openings as 11, the auxiliary band 9 having practically similar openings 12, these several 10 openings or orifices directing small streams of water or other agent upward. The body or upper annulus 8 may as shown have jet orifices or perforations 13 to direct streams of water or other extinguishing fluid down- 15 ward and upward at the proper angles against the upper part of the body and head. The base or floor annulus 7 has exteriorly the nipple 14 which as shown is connected by a pipe as 15 with the branch 15' of the main 20 or equivalent 16 which extends into the cabinet 2. In turn the body annulus 8 may be equipped with a nipple 8' likewise connected as by the pipe 17 with said branch 15'.

When the cabinet is closed and the fire extinguisher not in use both these parts 7 and 8 will be mounted in the cabinet 2 as shown for illustration in Figs. 1 and 3 at which time they can be suspended upon a suitable support or arm as 18. When they are thus 25 mounted the water supply valve 19 to which said support 18 is connected, is closed. By the withdrawal of the two members 7 and 8 from the cabinet, the valve 19 is released and is opened instantly by suitable means as 30 the spring 19' to effect the supply of water which passes from the main or supply pipe 16 to the flexible pipes 15 and 17 and from the latter to the members 7, 8 and 9. These two pipes 15 and 17 may be of any suitable 35 character preferably as may be inferred, being flexible, while the rings 7 and 8 need not necessarily be flexible but usually are of metal or some material possessing the requisite ability to maintain the desired shape.

40 45 Connected suitably with the upper annulus is a garment as 20 which is adapted to envelop the body of the user and to hang from about the neck. This garment is of fire-proof composition; it may for illustration be of asbestos cloth or something of a like nature, and it may have holes 20' to receive the arms of the wearer. When the two members 7 and 8 are incased as described, the garment 20 will be folded snugly against 50 the upper member 8 and will be maintained in this way in suitable manner as by the destructible strips as 21 which may be of paper and connected therewith as shown best in Fig. 8 and extending diametrically 55 of the upper ring. By breaking or rupturing these strips, and this can be readily accomplished, as will be understood, the garment will be dropped and can envelop the human body as the annulus 8 is being drawn 60 over the head to rest on the shoulders or

to be about the neck. There may be also connected with the upper annulus 8 the head or hood piece 22, and this may be drawn partially around the head from the back thereof, the streams of water from the upper annulus 8 being directed into the space or interval between the headpiece or hood 70 22 and the head of the wearer.

It will be remembered that the two pipes 15 and 17 are connected with the branch 15' 75 of the T at the upper end of the main 16. To the branch 15'' of said T I have shown connected the hose 25 having the nozzle 26, the hose being normally supported by the hook 27 extending from the back of the 80 cabinet 2. The branch 15'' is shown provided with a valve 28 by opening which water will be caused to flow through the hose 25 should occasion arise for the use of the 85 hose. The hose 25 can, if occasion is required be used and it is readily accessible. When out of use it is, of course, carried upon the hook 27 and the valve 28 is closed.

It is believed the operation of the apparatus will be readily understood. Normally 90 the doors 4 of the cabinet 2 are closed and maintained in such condition by the catch 5, the two annular members 7 and 8 and their adjuncts at this time being suspended by the arm 18. When it is necessary to use the apparatus the following procedure may be adopted: The catch 5 will be manipulated to release the doors 4 when they will be instantly opened by the springs 6 associated with their hinges. The two annular spraying members 7 and 8 will then be taken from the support or arm 18, thus permitting said support or arm 18 to be swung up by the spring means connected therewith in the manner described. This causes the flow of 105 water through the pipes or tubes 15 and 17. The ring or annular member 7 is placed on the floor and the user steps into it. The head is then passed through the annular member 8, thus breaking the paper tapes or 110 strips 21 and releasing the garment 20 which is wrapped snugly if necessary about the body, the arms being passed through the openings in the garment so as to be left free. If necessary the hood piece can be lifted up 115 and placed about the head. Inside the garment 20 as will be clear, there will be directed upwardly and downwardly streams of water and there will also be streams directed against the head.

To facilitate the dropping of the garment 20 it may as shown be provided near its lower end with weights as 30.

What I claim is:

1. A garment of fire-proof material combined with means associated with the garment for delivering a fire extinguishing fluid within the garment. 125

2. A garment of fire-proof material combined with an annular member from which 130

- the garment is suspended, and means for the delivery of a fire extinguishing fluid into the annular member, the annular member having means for the discharge of the fluid. 5
3. A garment of fire-proof material combined with an annular member from which the garment is suspended, and means for the delivery of a fire extinguishing fluid into the annular member, the annular member having means for the discharge of the fluid, and also having a head-piece connected therewith and to be fitted around the head. 10
4. The combination of a hollow annular member to be passed over the head, means for the delivery of a fluid to the annular member, the latter having outlets for the fluid, and a garment of fire-proof material suspended from the annular member, to be worn about the body and having holes for the passage of the arms of the wearer. 15
5. A fire extinguishing garment and fire extinguishing means connected with the garment, means for supporting the garment and the fire extinguishing means, and means for effecting the supply of a fire extinguishing fluid when the garment and the fire extinguishing means are taken from their support. 20
6. A garment of fire-proof material to be worn upon the body of a human being combined with means for the delivery of a fire extinguishing fluid on said body when the garment is thereon. 25
7. The combination of an annular member for the delivery of a fire extinguishing fluid, a garment, and rupturable means for holding the garment in folded relation with the annular member. 30
8. An annular tubular member having outlets for an extinguishing fluid, a garment to be worn by a human being, and rupturable strips extending across the annular member for maintaining the garment normally in folded condition. 35
9. A fire extinguishing appliance comprising an annular member in which a human being can stand, a second annular member to be worn about the body, the two annular members having outlets for an extinguishing fluid, a garment of fire-proof material connected with one of said annular members and to be worn upon the body of a 40
- human being, and means for supplying the fluid to the annular members. 55
10. A fire extinguishing appliance comprising an annular member in which a human being can stand, a second annular member to be worn about the body, the two annular members having outlets for an extinguishing fluid, a garment of fire-proof material connected with one of the annular members and to be worn upon the body of a human being, and means for supplying the fluid to the annular members. 60
11. A wall cabinet, means in the wall cabinet including a fire-proof garment to be worn by a human being and for the extinguishment of fire upon a human being, and means for supplying an extinguishing fluid to the extinguishing means when the same is withdrawn from the cabinet. 65
12. The combination of a cabinet having means for closing the same, means for normally holding the cabinet closing means in closed position, a source of fluid supply, a fire-proof garment to be worn by a human being, inclosed by the cabinet and removable therefrom, and means for the supply of the fluid from the fluid supplying means into the garment when the same is taken from the cabinet. 70
13. A cabinet, water supply means leading into the cabinet, fire extinguishing means including a fire-proof garment to be worn by a human being, suspended in the cabinet, and means for causing the flow of the water to the fire extinguishing means when the latter is dismounted and removed from the cabinet. 75
14. An annular fire-extinguishing tubular member having an interior projecting tube, and a second annular tubular extinguishing member within the other annular member connected with the tube, both annular members having perforations for the discharge of a fluid therefrom, and the two annular members being adapted to rest on a floor or other foundation and the outer one being adapted to receive a human being. 80
- In testimony whereof I affix my signature in the presence of two witnesses. 90
- JAMES O'LOUGHLIN.
- Witnesses:
- L. L. MARKEL,
HEATH SUTHERLAND.
